J. P. FARMER.
GAS STOVE BURNER.
(Application filed May 29, 1898.)

(No Model.)

UNITED STATES PATENT OFFICE.

JOHN P. FARMER, OF PORTLAND, OREGON, ASSIGNOR OF ONE-HALF TO
C. F. ADAMS, OF SAME PLACE.

GAS-STOVE BURNER.

SPECIFICATION forming part of Letters Patent No. 653,622, dated July 10, 1900.

Application filed May 29, 1899. Serial No. 718,693. (No model.)

To all whom it may concern:

Be it known that I, JOHN P. FARMER, a citizen of the United States, residing at Portland, in the county of Multnomah and State of Oregon, have invented a new and useful Gas-Stove Burner, of which the following is a specification.

My invention relates to burners designed for use in connection with gas-stoves and similar devices; and the object in view is to provide a burner and coöperating valve mechanism constituting an automatic gas cut-off whereby the extinguishment of the flame at the burner is followed by the closing of a gas-controlling valve to cut off the supply of gas, and thus prevent its escape without burning, and, furthermore, to provide a generating or pilot valve mechanism designed to control the admission of gas to the burner, to cause the actuation of the controlling-valve, and to provide means between the controlling-valve and the generating or pilot valve whereby the latter is closed simultaneously with the opening of the former; furthermore, to provide means whereby motion is communicated from a supply-valve to a generating or pilot valve, whereby the latter may be adjusted by means of the former to allow the communication of gas through the channel controlled by the generating or pilot valve to the burner, and also to provide a thermostatic burner-shell whereby the gas-inlet-controlling valve is actuated through the expansion and contraction of said shell; and in connection therewith to provide simple and efficient means for regulating the supply of air to the interior of the burner-shell.

Further objects and advantages of this invention will appear in the following description, and the novel features thereof will be particularly pointed out in the appended claims.

In the drawings, Figure 1 is a perspective view of a burner constructed in accordance with my invention. Fig. 2 is a longitudinal section of the same. Fig. 3 is a horizontal sectional view of the valve-casing and adjacent parts, showing the supply and controlling valves closed and the generating or pilot

valve in its normal or open position. Fig. 4 is a similar view showing the supply and controlling valves open, as when the burner is in full operation, the generating or pilot valve having been closed by the connecting-levers. Fig. 5 is a transverse sectional view of the valve-casing on the plane indicated by the line 5 5 of Fig. 3. Fig. 6 is a longitudinal section of the same on the plane indicated by the line 6 6 of Fig. 3.

Similar reference characters indicate corresponding parts in all the figures of the drawings.

1 designates a burner-shell constructed of material which is expansible by heat, such as hard brass or the equivalent thereof, said shell being of the star shape illustrated or of any other preferred form, with suitable burner-perforations in the upper surface thereof and having a central air-supply passage 2. The burner illustrated in the drawings is of sectional construction, comprising an upper member 1^a and a lower separable member 1^b, having a suitable supporting device 3. Communicating with the interior of the shell and preferably threaded upon a nipple 4, extending radially from the upper shell section or member, is a collar 5, forming an inlet-conductor in communication with a valve-casing 6, and in this conductor is a valve-seat 7, in operative relation with which is arranged a controlling-valve 8. The stem 9 of this controlling-valve extends through the burner-shell, preferably between the planes of the air-supply branch openings 10, which communicate with the above-described air-supply passage 2, and said valve-stem is constructed of a different material from the burner-shell and preferably of a metal having a lower ratio of expansion or having practically no expansion when subjected to heat, such as neutral steel. The valve-stem at that end remote from the controlling-valve is adjustably fitted in a radial opening in the shell, whereby the valve may be adjusted when the burner-shell is cold to snugly fit the valve-seat, and thus close the inlet-conveyer to exclude gas which may be contained in the valve-casing from the interior of the burner.

In practice said stem is preferably threaded in said opening in the burner-shell and its exposed end is constructed to form a wrench or key seat 11, whereby the rod may be turned 5 by the exterior application of a suitable tool to adjust the stem axially, and thus vary the position of the controlling-valve with relation to its seat to insure the tight gas-excluding seating of said valve when the burner is cold 10 or has cooled to a temperature less than that at which it would be maintained by the ignition of gas at the burner-openings. Also communicating with the burner-inlet passage or the bore of the conveyer between said controlling-valve seat and the burner is a generating or pilot channel 12, which extends into the valve-casing 6 and is fitted with a generating or pilot valve 13, the opening of said valve serving to allow gas within the valve- 15 casing to pass to the burner around or independently of the controlling-valve by which the main conductor connecting the burner with the valve-casing is closed. Also in communication with the interior of said valve-casing is a supply-pipe 14, fitted with a supply-valve 15, having an exposed or exterior handle 16, which may be of the ordinary or any preferred construction, whereby gas may be admitted from the supply-pipe to the interior of the valve-casing for communication 20 through the generating or pilot channel or through the main burner-inlet conductor to the interior of the burner-shell.

The generating or pilot valve is provided 25 with radial wings or shoulders 17 and 18, in operative relation with the former of which is arranged the extremity of a shifting arm 19, adapted to be actuated by the stem of the controlling-valve when the latter is moved to 30 unseat the controlling-valve in the burner-inlet conductor. Various means of connection between the controlling-valve stem and said shifting arm may be employed; but in the construction illustrated the controlling- 35 valve stem is provided with an extension 20, fitted terminally with a stop 21, preferably consisting of a nut threaded upon said extension and an operating-arm 22, pivotally mounted at one end in the valve-casing, and 40 having said stop on the valve-stem extension arranged in operative relation therewith at a point adjacent to said pivot, the free end of said operating-arm bearing upon the shifting arm at a point near the pivot of the latter. 45 Thus a slight axial movement of the valve-stem sufficient to unseat the controlling-valve will be communicated to the operating-arm 22 at a point near the pivot of the latter, and this motion, multiplied by the length of said 50 operating-arm, will be communicated to the shifting arm at a point near the pivot of the latter, and this motion will in turn be multiplied by the length of the shifting arm and 55 communicated to said shoulder or wing 17 of the generating or pilot valve to close said valve, and thus cut off the communication of

gas from the valve-casing to the burner through the generating or pilot channel which is controlled by said valve. Thus the wings or shouldered portion of the generating or pilot 60 valve constitutes a rocker with which co-operate multiplying-levers actuated by the thermostatic burner-shell through the draw-rod formed by the stem of the controlling-valve to cause the closing of the generating or pilot 65 valve simultaneously with the opening of the controlling-valve, whereby after a flame fed through the generating or pilot channel has existed for a sufficient length of time to heat and expand the burner-shell, and thus unseat 70 the controlling-valve, said generating-channel will be closed, and the burner will be fed solely through the main channel formed by the conveyer. Therefore should the flame at the burner be extinguished otherwise than 75 by cutting off the supply of gas by suitable manually-operated means provided for that purpose (and hereinafter described) the contraction of the burner-shell, due to the cooling thereof, will return the controlling-valve 80 to its seat, and thus automatically close the conveyer to prevent the escape of the gas.

Any suitable supply-valve mechanism may be employed in connection with the apparatus as above described to admit gas to the valve-casing for communication through the generating-channel to the burner; but in the drawings I have illustrated a stop-cock 15 similar in construction to those now in common use in connection with gas-stoves, the same, 90 or its stem, being provided with an ear, stud, or other projection 23 for contact with the shoulder or ear 18 of the generating or pilot valve rocker, said projection and wing or ear being so related that when the supply-valve 95 is closed the generating or pilot valve will be open. After the movement of the valve-stem to close the main burner-passage the parts 13, 19, and 22 are restored to their normal positions, as shown in Fig. 3, by manipulating the 100 valve-handle 16. Thus in operation when it is desired to light the burner the supply-valve is opened to admit gas to the valve-casing, and from said casing it passes through the generating-channel to the burner. After the flame 105 thus fed through the generating-channel has burned for a sufficient length of time to expand the thermostatic burner-shell the controlling-valve will be opened and the generating or pilot valve closed, as hereinbefore explained. Should the flame be extinguished, accidentally or otherwise than by closing the supply-valve, the controlling-valve will be automatically closed. On the other hand, if the supply of gas is cut off by closing the supply- 110 valve the movement of the latter will open the generating or pilot valve, whereupon the subsequent opening of the supply-valve to again start the burner will be accomplished by the communication of the gas through the 115 generating-channel. By having the stem 9 parallel to the perforated upper wall of the 120

burner the stem is uniformly heated throughout its length, thus hastening the opening of the valve 8.

The interior of the burner-shell is adapted to perform the function of a mixer, and in order that a combustion-supporting agent, such as atmospheric air, may be admitted thereto under control I provide the same with an inlet 24, provided with a disk-valve seat 25, having a port 26, and an adjustable disk valve 27, centrally pivoted upon said seat and having an opening 28, adapted to register with said port. By means of this disk valve a supply of air in any desired quantity may be admitted to the shell to serve as a combustion-supporting agent, the disk being provided with a milled periphery to facilitate the manual adjustment thereof.

It will be seen that the supply-valve, controlling-valve, and pilot-valve are all operatively coupled by suitable connections, so that the pilot-valve is automatically operated by either the controlling-valve or the supply-valve. The controlling-valve in the act of opening closes the pilot-valve, and the supply-valve in the act of closing opens the pilot-valve to admit gas to the mixing-chamber. As the supply-valve is closed the lever 22 will flex sufficiently to admit of said valve being closed.

Various changes in the form, proportion, and the minor details of construction may be resorted to without departing from the spirit or sacrificing any of the advantages of the invention.

Having described my invention, what I claim is—

1. The combination with a thermostatic burner-shell, a gas-conveyer, and a controlling-valve operatively connected to the shell for actuation thereby, of a pilot-channel, a pilot-valve therefor, a supply-valve, and connections between all of said valves whereby they are operatively coupled.

45 2. The combination with a thermostatic burner-shell, a gas-conveyer, and a controlling-valve having its stem operatively connected with said shell for actuation by the expansion and contraction thereof, of a generating or pilot channel, a generating or pilot valve controlling said channel, and operating connections between said controlling-valve and the generating or pilot valve, substantially as specified.

55 3. The combination with a thermostatic burner-shell and a communicating gas-conveyer, of a controlling-valve for said gas-conveyer actuated by said shell, a generating or pilot valve controlling an independent gas-channel, and operating connections between said controlling-valve and the generating-valve whereby the latter is closed simultaneously with the opening of the former, substantially as specified.

65 4. The combination with a thermostatic burner-shell and a communicating gas-con-

veyer, of a generating or pilot valve controlling an independent gas-channel, a controlling-valve-stem extension actuated by said thermostatic burner-shell, and means between said stem extension and the generating or pilot valve, whereby the latter is operated by the former, substantially as specified.

5. The combination with a thermostatic burner-shell and a communicating gas-conveyer, of a generating or pilot valve controlling an independent gas-channel, a controlling-valve-stem extension, actuated by said thermostatic burner-shell, an adjustable stop carried by said stem extension, and means, operated upon by said stop for actuating the generating or pilot valve, substantially as specified.

6. The combination with a thermostatic burner-shell and a communicating gas-conveyer, of a generating or pilot valve controlling an independent gas-channel, a controlling-valve-stem extension actuated by said thermostatic burner-shell, a shifting arm operatively related to said generating or pilot valve, and means for causing said stem extension to operate the shifting arm, substantially as specified.

7. The combination with a thermostatic burner-shell and a communicating gas-conveyer, of a generating or pilot valve controlling an independent gas-channel, a controlling-valve-stem extension actuated by said thermostatic burner-shell, a shifting arm operatively related to the generating or pilot valve, an operating-arm operatively related to said shifting arm, and means for communicating motion from said stem extension to the operating-arm, substantially as specified.

8. The combination with a burner and a communicating gas-conveyer, of a generating or pilot valve controlling an independent gas-channel, a controlling-valve-stem extension, a shifting arm operatively related to the generating or pilot valve, an operating-arm operatively related to said shifting arm, and a stop on said stem extension for contact with the operating-arm to communicate closing motion to the generating or pilot valve, substantially as specified.

9. The combination with a burner and a communicating gas-conveyer, of a generating or pilot valve controlling an independent gas-channel, a controlling-valve-stem extension, a shifting arm operatively related to the generating or pilot valve, an operating-arm operatively related to said shifting arm, and an adjustable stop carried by said stem extension and consisting of a nut threaded thereon for contact with said operating-arm to communicate closing motion to the generating or pilot valve, substantially as specified.

10. The combination with a burner having a gas-conveyer, and a thermostatically-actuated controlling-valve for said conveyer, of a generating or pilot valve controlling an independent gas-channel, operating connections

between the controlling-valve and the generating or pilot valve, for communicating closing motion to the former when the latter is opened, and a supply-valve provided with 5 means for communicating opening motion to the generating or pilot valve, substantially as specified.

11. The combination with a burner having a gas-conveyer, a thermostatically-actuated 10 controlling-valve for said conveyer, of a generating or pilot valve controlling an independent gas-channel, operating connections between the controlling-valve and the generating or pilot valve, for communicating closing motion to the latter when the former is opened, a supply-valve, and means for 15 communicating opening motion to the generating or pilot valve from the supply-valve, as the latter is closed, substantially as specified.
12. The combination with a burner having a gas-conveyer, a thermostatically-actuated 20 controlling-valve for said conveyer, of a generating or pilot valve controlling an independent gas-channel, operating connections 25 between the controlling-valve and the generating or pilot valve, for communicating closing motion to the latter when the former is

opened, a supply-valve, and coöperating projections on said generating and supply valves whereby opening motion is communicated to 30 the former during the closing motion of the latter, substantially as specified.

13. The combination with a burner having a gas-conveyer, a thermostatically-actuated 35 controlling-valve for said conveyer, of a generating or pilot valve controlling an independent gas-channel and having a winged rocker, a shifting arm operatively related to said rocker, means operated by the controlling-valve stem for actuating said shifting 40 arm to close the generating or pilot valve, and a supply-valve having a projection for engagement with a wing or shoulder of said rocker to communicate opening motion to the generating or pilot valve, substantially as 45 specified.

In testimony that I claim the foregoing as my own I have hereto affixed my signature in the presence of two witnesses.

JOHN P. FARMER.
